DESIGN FOR A DROPPER BULB OR SIMILAR ARTICLE

George M. Scattergood, Lancaster, Pa., assignor
to Armstrong Cork Company, Lancaster, Pa., a
corporation of Pennsylvania

Application July 16, 1940, Serial No. 93,682

Term of patent 14 years

To all whom it may concern:

Be it known that I, George M. Scattergood, a citizen of the United States, residing in Lancaster, county of Lancaster, and Commonwealth of Pennsylvania, have invented a new, original, and ornamental Design for Dropper Bulbs or Similar Articles, of which the following is a specification, reference being had to the accompanying drawing, forming a part thereof, in which:

Figure 1 is a front elevational view of a dropper bulb or similar article embodying my new design; and

Figure 2 is a vertical sectional view thereof, taken substantially through the center of the article in Figure 1.

I claim:

The ornamental design for a dropper bulb or similar article, substantially as shown.

GEORGE M. SCATTERGOOD.
